UNITED STATES PATENT OFFICE.

EMMANUEL MOOR, OF MONT PELEREN, SWITZERLAND.

KEYBOARD FOR MUSICAL INSTRUMENTS.

Application filed February 7, 1922, Serial No. 534,739, and in Germany May 27, 1921.

This invention relates to pianoforte and like musical instruments having striking mechanism of the kind described in my prior U. S. patent application filed on November 5 9th, 1920 under Serial Number 422,836, wherein is described means for causing each 10 string to vibrate by any of three various actions, viz, by means of a key of either of two key-boards, or by means of the lever of 15 an octave coupler provided in one of the 20 said key-boards.

The object of the present invention is to 15 provide means for rendering the said actions freely independent and prevent interference 20 therebetween. Accordingly to the invention, 25 automatic escapements allowing the return into the rest position of the wippens acting upon the hammers are provided between the 30 said wippens and the jacks actuating said 35 wippens either under the influence of the 40 keys or of the coupling mechanism.

The drawing accompanying this specification 25 is a diagrammatic view of the essential parts shown in longitudinal side section of a 30 piano mechanism constructed according to 35 the invention.

Referring to the drawing, *a* is a key of the 30 upper key-board A and *b* a key of the lower 35 key-board B of the piano having two key-boards. Corresponding keys of the two key-boards are arranged in line one above the other but are adapted to strike notes distant 40 from one another by an octave. For this purpose, the levers of the keys are oblique, as represented by means of hatchings on one 45 part of said levers. Similarly, the lever *c* of the coupling mechanism is arranged obliquely and is actuated by a key distant by one octave from the key corresponding to 50 the string caused to be struck by said lever.

The coupling mechanism is put into operative 45 position by means of a pedal *d* adapted to lift the fulcrum *l* of the lever *c* through the rod *m*, lever *o* and movable fulcrum 50 support *p*. The coupling mechanism may be then actuated by any of the keys *b*, by means of a pusher *e* which, when the coupling lever *c* is elevated, is engageable by said key *b*. The wippen *f* of the mechanism of each 55 hammer may be actuated either directly by one of the keys *a* or directly by one of the keys *b* or by the lever *c* of the octave coupling mechanism. On this wippen *f* is fixed a jack *g* acting upon the hammer, the latter not being represented.

Between the key *a* and the jack *g*, an

escapement *h* is provided, so that even when this key *a* is held depressed, the jack *g* is released therefrom and it is thus possible again to actuate the jack *g*, either by means 60 of the key *b* or by the coupling lever *c*.

According to the invention, automatic escapements *h*, *i* are inserted between the keys *a*, *b*, and the lever *c*, on the one hand, and the jack *g*, on the other hand. Said automatic escapements allow the independent return into the rest-position of each of the various organs *a*, *b* or *c*. Both the lever of the key *b* and the lever *c*, act, as represented, upon the same intermediate wippen *k*, and thus, only one actual escapement mechanism is necessary for the key *b* and the lever *c*.

The form of escapement is represented diagrammatically in the drawing, and it comprises a form of escapement already well 75 known in the art of piano manufacturers. In the form shown, the escapement mechanism of the key *a* consists of an angular lever *h'* pivoted to the key *a* and engageable with the wippen *f*, a trip *h*² being provided 80 to disengage the lever *h'* from the wippen *f* subsequent to the actuation of the hammer associated with said wippen. In the case of the key *b*, the angular lever *h'* is pivoted to the intermediate wippen *k* and engages an 85 extension *f'* of the wippen *f*. I do not wish, however, to be limited to this form, but may adopt other forms suitable for any particular arrangement of repeating mechanism used in the construction of pianos. 90

I claim:

In a musical instrument of the character described, a main wippen, a group of keys common to and adapted to act upon said main wippen, an automatic escapement interposed between one of the keys and the main wippen, an intermediate wippen carried by the other key, an automatic escapement interposed between the intermediate wippen and main wippen, the several automatic escapements permitting the return of the main wippen independently of the keys, a key operable lever, and means connecting the lever with the intermediate wippen whereby movement of the lever is transmitted to the main wippen through the auxiliary wippen and the second mentioned automatic escapement. 100 105

In testimony whereof I hereunto affix my signature.

EMMANUEL MOOR.
